UNITED STATES PATENT OFFICE.

EDGAR M. BOUTON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELEVATOR CONTROL SYSTEM.

Application filed February 16, 1922. Serial No. 536,872.

My invention relates to motor-control systems and it has particular relation to such systems of control as are employed in connection with elevators, hoists, and the like.

5 One object of my invention is to provide means for operating an elevator car at normal speed or at an extremely slow speed, as may be desired.

Another object of my invention is to provide 10 a system wherein an elevator car or other device may be controlled with extreme accuracy within predetermined limits of motion.

Many systems of control have been employed 15 in connection with elevators and hoists in an endeavor to secure accurate stops or landings, independently of the skill of the operator. Such systems are, as a rule, rather complicated and, in some instances, not 20 sufficiently effective or satisfactory.

My invention is particularly adapted for 25 use in connection with high-speed elevator machines of the traction type, which are generally understood as comprising a motor-operated driving-sheave and a secondary sheave. The hoisting cables are wrapped 30 about the sheaves in such manner that effective traction is established between the driving sheave and the cables for operating the car.

In addition to the standard elevator machine and the usual control apparatus, I provide 35 an auxiliary hoisting machine for connection, by means of an electro-magnetic clutch, to the secondary sheaves. My system of control is arranged for selectively operating the car by the one or the other of these hoisting machines. The control of the main motor is effected by means of the usual type 40 of car switch whereas the auxiliary motor is controlled by means of a pair of reversing switches that are mounted on the car and actuated by cams in the elevator hatchway. These cams are effective to control the operation 45 of the elevator car within predetermined limits of travel, with respect to each floor level.

The single figure of the drawing is a diagrammatic representation of circuits and 50 apparatus embodying my invention.

The main hoisting motor, having an armature 1 and a field-magnet winding 2, is operatively connected to line conductors 3 and

4 through reversing switches 5 and 6. The main driving-sheave 7 is mounted on the 55 armature shaft. The usual form of electro-magnetic brake 8 is provided.

A starting resistor 9 may be controlled by 60 an accelerating switch 11 in any well-known manner. A controlling switch, having an operating lever 12, is located within, and 65 normally controls the operation of, the car 13. Auxiliary reversing switches 14 and 15 co-operate with a stationary contact member 16 to control an auxiliary hoisting motor 20 having an armature 17 and a field-magnet winding 18. Switch contact members 14 and 15 are normally maintained in their illustrated positions by means of springs 19 and 21.

A cam 22 is located in the hatchway, adjacent to each floor 23, for effecting the control of the armature 17 by means of reversing switches 24 and 25. A starting resistor 26, controlled by an accelerating switch 27, 75 is provided for the auxiliary motor 20. The auxiliary motor, with an electromagnetic brake 28, is connected, through suitable gearing 29 and an electromagnetic clutch 31, to drive the secondary sheave 32. Either the 80 main or the auxiliary motor may be employed for operating the elevator car 13.

In one instance, the sheave 7 operates as the driving member, that is, while the clutch 31 is released, whereas, when the sheave 32 85 is operated as the driving member, the clutch 31 is effective to transmit power from the armature 17. In the latter case, the electromagnetic brake 8 is released and the main armature 1 is driven idly, together with the sheave 7, by means of the hoisting cables that control the movements of the elevator car.

An auxiliary relay 33 controls the electromagnetic brake 28 and co-operates with a normally closed relay 34 and a centrifugal 95 governor 35, for controlling the electromagnetic brake 8. The centrifugal governor 35 is operatively connected, in any convenient manner, to function in accordance with the speed of the elevator car 13.

The operation of my system will be more clearly understood from the following description. In normal operation, the elevator car 13 is governed, in a well-known manner, by the operating lever 12 of the car switch 105 which controls the direction of rotation of

the main armature 1 by means of reversing switches 5 and 6. This much of the operation is so well understood and so old in the art, that further detailed description is considered unnecessary.

It may be assumed, however, that the car 13 is operating at normal speed and that the operator returns the lever 12 to its inoperative or illustrated position to effect a landing, substantially level with the floor 23. If the car is moving upward and tends to stop below the level of the floor 23, the cam 22 actuates switch member 16 to continue the upward movement of the car, by means of the auxiliary hoisting mechanism and independently of the operator. It may be assumed that the governor-switch members 36 and 37 respectively occupy the positions illustrated in the drawing and which correspond to a very slow operating speed.

An auxiliary circuit for effecting upward movement of the car 13 extends from the line conductor 3 through conductor 38, the operating coil of relay 33, the operating coil of reversing switch 24, conductor 39, contact members 14 and 16, governor switch 37, car switch members 41 and 42 and conductor 43 to line conductor 4. The relay 33 closes to establish a circuit for the operating coil of electromagnetic brake 28, extending from line conductor 3 through conductors 38 and 44, relay 33 and the operating coil of brake 28 to line conductor 4, thereby effecting a release of the brake 28. Electromagnetic brake 8 is also released by the energization of an auxiliary operating coil 45, connected in series relation with the armature 17, the circuit for which extends from line conductor 3 through resistor 26, switch 24, operating coil 45, relays 33 and 34, armature 17 and switch 24 to line conductor 4. Power is supplied to the auxiliary armature 17 by the closure of "up" reversing-switch 24, whereby, upon release of brake magnets 8 and 28, power is applied through the clutch 31 for driving the sheaves 32 and 7.

It is obvious that the auxiliary coil 45, which is in series relation with armature 17, is energized in proportion to the elevator load and the current traversing the armature 17. With light load, for example, the main brake 8 is not fully released and imposes additional load on the auxiliary motor. Consequently, the auxiliary motor always operates under load and at a uniform speed.

It is also obvious that a shunt coil may be employed, in lieu of series coil 45, in which case the main brake 8 will be fully released irrespective of load conditions; the coil would be connected to line conductors 3 and 4, through relays 33 and 34.

When the car 13 has attained a level with the floor 23, switch member 14 returns to its normal or illustrated position to interrupt the operating circuit through contact mem-

ber 16, as previously traced. The switch 24 opens to interrupt the operating circuit for armature 17, and relay 33 opens to effect the application of the brakes 8 and 28.

A movable clutch member 46, during the operation just described, is maintained in engagement with stationary clutch member 47 by means of a compression spring 48. However, during normal operation of the elevator, the clutch members 46 and 47 are disengaged by means of an operating coil 49, which is energized simultaneously with the main operating coil 50 of the brake 8. As illustrated, these coils are connected in series relation.

When the car 13 is operating above a predetermined speed, governor switch 36 is closed and a circuit is established for an auxiliary coil 51, which operates independently of coil 49, for maintaining the clutch 31 inoperative. A circuit for coil 51 extends from line conductor 3, through conductor 52, governor switch 36, coil 51 and operating coil of relay 34, to line conductor 4.

It will be noted that relay 34 is open, during normal operation of the main motor and as long as the elevator car 13 is operating above a predetermined speed, at or above which the governor switch 36 remains closed.

Therefore, slow-down of the main hoisting motor to a predetermined degree must be effected before the auxiliary brake coil 45 can be energized through relay 34. The auxiliary clutch-holding coil 51 also is deenergized by the opening of governor switch 36, and the clutch 31 does not become effective as a driving member until the speed of the elevator car has been reduced to a proper value, corresponding to the operating speed of the auxiliary motor 20. In other words, the relative speeds of armature 17 and sheave 32 are controlled by means of the governor 35 prior to the engagement of clutch members 46 and 47. It is manifestly impractical to drive the auxiliary motor at a speed corresponding to the highest operating speed of the elevator, for which reason the clutch mechanism is provided.

Referring again to the slow-speed operation, it is evident that downward movement of the car 13 is effected or continued upon the engagement of contact members 15 and 16, as when the car tends to stop above the level of the floor 23. In this case, the cam 22 maintains switch members 15 and 16 in engagement until the car is substantially level with the floor 23, corresponding to its illustrated position. The downward movement of the car is effected by the closure of reversing switch 25 and relay 33, a circuit for the operating coils of which extends from line conductor 3 through conductor 38, operating coil of relay 33, operating coil of switch 25, switch contact members 15 and 16, governor switch 37, car switch members 41 and 42 and conductor 43 to line conductor 4. All other

operating circuits are as previously described in connection with the upward movement of the elevator.

It will be recognized that my system of control may be readily applied to any standard elevator equipment and lends itself to such applications in a very practical manner. Assuming that the elevator is designed for a normal operating speed of say five hundred feet per minute, the auxiliary machine for driving the secondary sheave may be very small, to effect operation of the car at say twenty-five feet per minute. The auxiliary machine is not subjected to heavy strains, since these are borne by the main hoisting machine and the secondary sheave. The torque necessary for operating the car by means of the secondary sheave at the reduced speed is low, compared to that required of the main motor to operate the car at its normal speed. Also, in stopping, the

main brake is applied and assumes the major portion of the work necessary to bring the elevator to rest.

I claim as my invention:

1. The combination with an elevator and a main hoisting motor therefor, of leveling means for said elevator comprising an auxiliary motor and braking means for variably loading said auxiliary motor to secure uniform leveling operations of said elevator.

2. The combination with a main motor for operating an elevator car and a brake therefor, of a coil independent of said motor for controlling the brake, an auxiliary motor for said car, and a coil in series relation with the armature of said auxiliary motor for controlling said brake.

In testimony whereof, I have hereunto subscribed my name this 2nd day of February, 1922.

EDGAR M. BOUTON.
